[57] CLAIM

The ornamental design for an abdominal exercise mat, as shown and described.

DESCRIPTION

FIG. 1 is a top front perspective view of an abdominal exercise mat showing our new design;
FIG. 2 is a rear back perspective thereof;
FIG. 3 is a top elevational view thereof;
FIG. 4 is a bottom elevational view thereof; and,
FIG. 5 is a right side elevational view thereof; and a left side elevational view appears as a mirror image of the right side elevational view.
